UNITED STATES PATENT OFFICE.

JOSÉ ANGELES MORENO, OF GALVESTON, TEXAS.

CHAIN-OPERATING DEVICE.

Application filed December 6, 1926. Serial No. 153,028.

This invention relates to an improved chain operating device and has more specific reference to a structure which may be referred to as a quick service light-weight 5 chain block and operating crank therefor.

One feature of construction is the novel casting which is rotatably mounted upon a longitudinally adjustable journal, the casting including a relatively large worm gear 10 and an especially constructed and relatively smaller sprocket for the chain.

Another feature of construction is spring means provided for normally sliding the journal in a manner upon said frame to 15 disengage the worm gear from the operating worm drive.

A further feature of the invention is a special crank including pawl and ratchet mechanism and an adjustable hand grip for 20 convenience of manipulation and operation.

Other features and advantages of the invention will become apparent from the following description and drawing.

In the accompanying drawings forming a 25 part of this application and in which like numerals are employed to designate like parts throughout the same:

Figure 1 is an end elevation of the complete device,

Fig. 2 is an enlarged view in elevation and section looking at the side of the structure,

Fig. 3 is a section on the line 3-3 of Fig. 2,

Fig. 4 is a section taken approximately upon the plane of the line 4-4 of Fig. 2,

Fig. 5 is a detail elevational view,

Fig. 6 is a section through the sprocket.

Referring to the drawings in detail it will 40 be seen that the reference character 1 designates generally the frame which comprises a pair of spaced parallel side bars 2 connected together by spacing bolts 3 and 4 having retaining nuts 5. The bolt 3 carries a supporting hook 6. The central portions of the side bars are formed with oppositely disposed elongated slots 7 which serve a purpose to be hereinafter described.

Located between the side bars is the special casting 8 which includes the large worm gear 9 and special sprocket members 10 having cooperating recesses 11 and 12 for action with the links 13 of the chain 14. This chain is provided at its free end with 55 a hoisting hook 15. This casting 8 is mounted for rotation upon a journal 16 having

reduced end portions 17 as represented in Fig. 1 and slidably mounted in the correspondingly shaped slots 7. The journals terminate in reduced extensions 18 and coil 60 springs 19 are connected therewith at one end and at their opposite ends with stationary anchoring pins 20 carried by the side bars of the frame. In this connection I would direct attention to a laterally extending arm 21 having a right angularly disposed end portion 22 forming a chain guard. The worm driving element or screw 23 is rotatably mounted in a bushing 24 cast integral with the lower portion of the frame. 70 At least one end of this element is formed with a polygonal portion 25 with which the operating crank 26 is detachably connected.

Considering now the crank member 26 it will be seen that this embodies an adjustable 75 hand grip 27 held in place by a keeper including a polygonal portion 28 and a cylindrical portion 29. This keeper is held in operative position by a spring 30 which cooperates with a pawl 31 in turn cooperating 80 with a ratchet wrench 32. This allows the hand grip to be adjusted to any one of the positions represented in Fig. 2 for instance and also allows a step-by-step operation of the ratchet wrench.

In practice one end of the chain is suitably anchored on the supporting frame and as soon as the load is engaged by the hook 15 the worm gear is moved downwardly 90 against the tension of the springs 19 into mesh with the threads on the worm 23 thus providing a positive driving action between the worm and gear through the medium of the hand crank and transmitting such power to the sprocket for elevating the chain in 95 a customary step-by-step manner. To permit quick adjustment of the chain, the hook 15 is disengaged from the load whereupon the springs 19 pull the journal carrying the worm gear 9 upwardly so as to disengage 100 the worm gear, allowing the entire casting 18 to rotate freely as desired.

It is believed that by considering the description in connection with the drawing a clear understanding of the construction 105 as well as of the operation and features of the invention will be had and therefore, a more lengthy description is thought unnecessary.

I claim:

In a hoist of the class described, a pair 110 of spaced parallel frame members attached at each end and provided with aligned slotted

openings intermediate their ends, a journal disposed between said members with its end slidably carried in said openings and provided with flat sides whereby to prevent rotation thereof, spring means carried by the members and attached to the ends of the journal adapted to urge the same toward one end of the frame member in the openings, a worm gear freely mounted for rotation on the journal, a sprocket formed integrally therewith, a guard cooperating with the sprocket for retaining a chain thereon, a worm supporting casting carried at one end

of the member, a worm rotatably mounted thereon arranged for engagement with said gear, said worm having operating means attached thereto, said casting forming an attaching means for one end of a chain extending over the sprocket and adapted upon having its free end attached to an object to move the journal toward the opposite end of the frame member so as to engage the gear with the worm.

In testimony whereof I affix my signature.

JOSÉ ANGELES MORENO
